DESIGN FOR A SIGNALING DEVICE

Fred William Billig, Jackson, Mich., assignor to
The Sparks-Withington Company, Jackson,
Mich., a corporation of Ohio

Application February 24, 1933, Serial No. 47,307

Term of patent 7 years

To whom it may concern:

Be it known that I, FRED W. BILLIG, a citizen of the United States, residing in the city of Jackson, in the county of Jackson and State of Michigan, have invented a new, original, and ornamental Design for a Signaling Device, of which the following is a specification, reference being had to the accompanying drawing, forming part thereof.

Figure 1 is a perspective view of the signaling device, showing my new design.

Figure 2 is a top plan view of the same.

Figure 3 is a side elevation of the signaling device.

Figure 4 is a rear elevational view of the signaling device.

I claim:

The ornamental design for a signaling device substantially as shown.

FRED WILLIAM BILLIG.
